HOLDER FOR FOOD BOWLS FOR PETS

Tony Robert, 5701 Southwest Freeway,
Houston, Tex. 77027

Filed June 23, 1969, Ser. No. 17,804

Term of patent 14 years

Int. Cl. D30—02

U.S. Cl. D30—13

FIG. 1 is a perspective view of a holder for food bowls for pets, showing my new design;

FIG. 2 is a top plan view of the same;

FIG. 3 is a side view of the same; and

FIG. 4 is an end view of the same.

The dotted lines showing of the bowls in FIGURE 1 is for illustrative purposes only.

I claim:

The ornamental design for a holder for food bowls for pets, as shown and described.
